US00D332936S

United States Patent [19]

Lawrence

[11] Patent Number: Des. 332,936

[45] Date of Patent: ** Feb. 2, 1993

[54] FLUID POWER ELECTRICITY GENERATOR

4,740,725 4/1988 Charron

[76] Inventor: David Lawrence, P.O. Box 74,
Modoc, S.C. 29838

[**] Term: 14 Years

[21] Appl. No.: 511,532

[22] Filed: Apr. 20, 1990

[52] U.S. Cl. D13/112
[58] Field of Search D13/112, 114; D23/233,
D23/245, 248; 310/11, 40 R, 52, 75 R; 251/315

[57] CLAIM

The ornamental design for a fluid power electricity generator, as shown and described.

DESCRIPTION

FIG. 1 is a front and upper left perspective view of a fluid power electricity generator showing my new design;

FIG. 2 is a front elevational view thereof;

FIG. 3 is a rear elevational view thereof;

FIG. 4 is a top plan view thereof; and,
FIG. 5 is a left end elevational view thereof, the right end elevational view thereof being a mirror image.
